ARTIFICIAL FISHING BAIT

Joe Kautzky, Fort Dodge, Iowa

Application June 27, 1952, Serial No. 20,377

Term of patent 14 years

(Cl. D31—4)

To all whom it may concern:

Be it known that I, Joe Kautzky, a citizen of the United States, residing at Fort Dodge, in the county of Webster and State of Iowa, have invented a new, original, and ornamental Design for an Artificial Fishing Bait, of which the following is a specification, reference being had to the accompanying drawing, forming a part thereof.

Fig. 1 is a side view,

Fig. 2 is a top plan view,

Fig. 3 is a front view, and

Fig. 4 is a cross-sectional view taken on line 4—4 of Fig. 2 of an artificial fishing bait, showing my new design.

I claim:

The ornamental design for an artificial fishing bait, substantially as shown.

JOE KAUTZKY.
